U.S. 565

Julius Holzer, of Spring Garden, Pa.

Assignor to

James G. Abbott & Archibald Lawrence, of same place-
Letters Patent No. 565- Dated May 10th 1853,

uuuuu

The schedule referred to in these Letters Patent and making part of the same

uuuuuuuu

To all whom it may concern:

Be it known that I, Julius Holzer, of Spring Garden,
in the County of Philadelphia, and State of Pennsylvania have invented or produced a
new and original design in Cook Stoves Called the
"Enchantress,"

and I do hereby declare that the following is a full clear and exact description of the

same; reference being had to the annexed drawings, forming part of this specification, in which

Figure 1. is a side elevation of the stove.

Figure 2. is a front elevation of same; and

Figure 3. is a rear elevation.

Symmetrical ornaments in the several designs, have but half their details shown.

Similar letters of reference in the several figures denote the same part of the stove or design.

The panels of the front doors A, are raised by the ogee moulding a, and surrounded by the bead b; on each is the ornament B, in bas-relief composed of the foliage c, entwined with the vines d, and bearing the radial and projecting figures e, and f, the whole having the arrangement and configuration shown in figure 2.

Each side plate C, is surrounded by the moulding D, and has upon it the oven door E, and panel F, the latter on one side movable, and forming the feed door. Above the door E in raised capitals is the inscription "Enchantress", and below the oven door E, "Patented 1853," in raised capitals and numerals. The oven door E, is raised above the side plate C, by the ogee moulding H, and the panel surrounded by the bead I; upon the panel is the ornament J, in bas-relief, composed of the foliage f, entwined with the vines g, surrounding the elliptical elevation h, and bearing the radial projections i, and globular projections K, the whole having the arrangement and configuration fully set forth in figure 1.

The panel F, is raised above the surface of the plate C, by the moulding P, similar to those on the doors A, and E, and is surrounded by the bead Q; it bears the ornament R, in bas-relief composed of the foliage m, vines n, projections o, and elliptical figure p, arranged and having the configuration shown in figure 1.

The back plate S, is ornamented by the beads q, enclosing the rectangles T, as shown in figure 3.

The front foot U, is of the form shown in figure 1, with the

3

Wes 565

face sunken, and ornamented with the projections x, and configuration of the rim x, as shown fully in figure 1. The rear foot V, is of the same form as the front feet U, and is ornamented in a similar manner, the particular configuration is fully set forth in figure 3.

What I claim as my invention or production and desire to secure by Letters Patent, is

The configuration and arrangement of the ornaments in basrelief and mouldings on the doors A, E, & F, plates C & S, and feet U, & V, as fully set forth and described in this specification and annexed drawings, forming the ornamental design of the cook stove designated as the "Enchantress".

In testimony whereof, I have hereunto signed my name before two subscribing witnesses.
